UNITED STATES PATENT OFFICE.

ALFONSO A. RICHARDSON, OF NEW YORK, N. Y.

BUILDING CONSTRUCTION.

1,330,347.

Specification of Letters Patent. Patented Feb. 10, 1920.

Application filed December 3, 1917. Serial No. 205,070.

To all whom it may concern:

Be it known that I, ALFONSO A. RICHARDSON, a citizen of the United States, residing at New York city, N. Y., have invented certain new and useful Improvements in Building Construction, of which the following is a clear, full, and exact description.

This invention relates to improvements in building construction, of the type in which the parts can be made up and afterward quickly assembled. One of the objects of the invention is to provide a cheap construction, especially adapted for hot climates. Another object of the invention is to enable a building of the bungalow type to be put up cheaply and quickly, without necessitating the use of wood, nails, or the like. Still another object of the invention is to provide any desired lengths of material to be used in wall or partition construction, said lengths of material being non-metallic and comprising a web of open-mesh fibrous fabric which carries a plurality of slabs or panels, such for instance as plaster board, in which the meshes of the fabric are embedded, said slabs or panels being suitably separated so that the webs with the panels thereon may be folded up for convenient storage or transportation.

These being among the objects of the present invention, the same consists of certain features of construction and combinations of parts to be hereinafter described and then claimed with reference to the accompanying drawings illustrating one embodiment of the invention, in which

Figure 1 is an elevation of a portion of a building, comprising a skeleton frame-work to which are attached partition or wall members;

Fig. 2 is a perspective view of a fragment of the panel web of fabric folded up;

Fig. 3 is an enlarged sectional view on a plane just above one of the horizontal metal bars;

Fig. 4 is a perspective view of a detail, showing the principal means for anchoring the wall or partition members;

Fig. 5 is an enlarged detail view showing the fibrous fabric embedded in adjacent panels or slabs and a supporting bar passing through certain meshes of the fabric;

Fig. 6 is an enlarged section on the line

6—6 Fig. 1, showing the wall or partition members more in detail;

55

Fig. 7 is a sectional view of a complete wall provided with the present improvements;

Fig. 8 is a modification; and

Fig. 9 is a perspective view of another form of a horizontal supporting member.

Referring to the drawings, the webs 10 of fabric are provided with open meshes of ample size for the insertion of supporting members, and said fabric may be composed of lengths of cord or rope 12, which may be woven or knitted together, or which may be knotted together at the point of intersection of said lengths. Preferably, the fibrous cord or rope is made of some strong and comparatively cheap fibers, such as those of Sisal grass. Cord or rope made of such grass usually has numerous fibers or ends, such as 13, projecting therefrom. These projecting fibers or ends 13 are usually individual and untwisted, and have considerable tensile strength if the cord or rope is made of Sisal grass. Each web 10 of the said open-mesh fabric is provided with slabs or panels 14 which are spaced apart at 15 80 and which preferably run parallel with each other, so that the web with the slabs thereon can be folded up as shown in Fig. 2. The panels or slabs 14 may consist of plaster board or any suitable material, such as 85 cement, pulp of waste material or the like, which can be molded into shape upon either or both sides of the fabric webs, so that the meshes of the webs will be embedded in the plastic composition, which will thereafter 90 set and harden so as to form hard slabs or panels supported by the webs. It will be seen that not only by reason of the twisted and fibrous character of the rope or cord, the fabric and the slabs or panels will be 95 firmly bound and cemented together, but that the integrality of each slab or panel is further maintained by the anchorage or hold afforded it by the projecting fibers or ends 13.

The webs or strips 10 of fabric will not only have open meshes between the slabs or panels, but preferably the end meshes 16 project beyond the end slabs or panels in the form of loops, as clearly shown in Fig. 105 1. These bared end meshes or loops 16 are

adapted to receive insert or end rods 17, 18, which are run through said end meshes, the adjacent ends of said rods being inserted in sockets 19 which are carried by the end uprights 20 of the eventual skeleton frame of the wall or partition. The sockets 19, as shown clearly in Fig. 4, are preferably composed of strips of metal bent into suitable shape to form sockets and which are riveted or otherwise secured to the metallic uprights 20, said sockets being spaced suitable distances apart corresponding with the width of the webs of fabric to be employed. The sockets 19 support the intermediate ends of the insert or end rods 17, 18, while the upper and lower ends of each longitudinal series of said rods are suitably anchored in the floor and ceiling of the structure, which may be of suitable material. Intermediate metallic uprights, such as 21, are inserted into some of the meshes of the fabric which are exposed between the slabs or panels 14, and with the horizontal metal rods or bars 22 they form a part of the skeleton frame comprising them and the end uprights 20.

A wall or partition may be built up as follows: A suitable ceiling and floor being connected by end uprights 20, which are spaced at the desired distance apart, are provided. These uprights will be so placed that the sockets 19 thereon will be presented toward each other in the plane of the ultimate wall or partition to be formed. An insert or end rod is then inserted into the series of meshes exposed at each end of the web or strip 10. One of said rods is then anchored to the floor at its lower end, and its upper end is inserted into the socket 19 so that the exposed end meshes of the fabric will be held close to the upright 20, to which said insert rod has been applied. The said web containing an insert or end rod in the meshes at the other end is now stretched across from upright to upright, and the lower end of said rod is suitably engaged with the floor and the upper with the socket of that upright, as was the case before.

Over the wall or partition member consisting of the so applied web of paneled fabric, there is placed one of the horizontal rods or bars 22, the ends of the same being suitably attached to the uprights 20 as by passing wire ties, such as 23, through a hole in the end of said horizontal bar and through the adjacent socket 19 and twisting the ends of the wire together to form a tie. The said horizontal member 22 of the skeleton structure may desirably consist of a channel bar 60 of I-shape, as shown in Fig. 4, so that the groove in its lower surface will receive the upper edges of the panels or slabs of the web or strip 10 which has been already applied in position, as stated. The groove in the upper surface of said channel bar will re-

ceive the lower edges of the slabs or panels of the next web or strip 10, which is of the same construction as the paneled web or strip before described, and which is attached at its ends to the uprights 20 in a similar way. This process is continued until a complete wall or partition extending from floor to ceiling is produced, although previously to the completion thereof or after its completion intermediate uprights, such as 21, are passed at suitable intervals through certain of the meshes of the fabric exposed at the spaces 18, but not necessarily through all of the exposed meshes at all of said spaces. The said intermediate uprights can pass through holes, such as 24, in the horizontal rods or bars 22. If preferred, the intermediate upright bars or rods 21 can be made of lengths such as the insert or end rods 17, 18, which will enable the more convenient application of the said intermediate uprights to the structure. The horizontal bars may evidently be flat as at 26, Fig. 9.

It is obvious that the described structure can be stiffened in any suitable manner if it is not stiff enough.

Not only does the described construction of the wall or partition members of fibrous fabric and plaster board or the like provide a cheap construction, but it can be made wherever the buildings are to be put up, while the metal parts can be shipped from some other place. The flexibility of the open meshes of the fibrous fabric enables the same to be readily engaged over the supporting bars or rods, which can therefore be located directly in the plane of the slabs or panels. After the structure, as described, has been erected so as to form a room or building, the walls or partitions will preferably be plastered at both sides, one of the layers of plaster being indicated at 25, Fig. 7, which is a cross-section of a finished wall or partition in which one side only is plastered. It will be noted from this figure that the finishing plaster will enter all crevices or gaps in the structure and that at intervals it will embed certain meshes of the fabric exposed to it, so that when the finishing layers of plaster set and harden, they will be firmly bound and cemented to the interior structure of the wall or partition, thereby forming a substantial structure.

In the modification, Fig. 8, the panels are shown as completely embedding the meshes of the fabric; and Fig. 2 shows the same for the sake of simplicity of illustration.

In applying the plastic composition to the fabric to form the panels or slabs 14, it is preferable to form them at one side of the fabric, so as to leave some of the fabric exposed at corresponding sides of the panels, as shown in Fig. 6, so that the fabric will be partly bared at said sides. On applying a layer of plaster to a wall containing such a

construction, it will adhere to projecting fibers and to the exposed portions of said fabric at the said sides of the panels, and it may not be necessary to plaster the other 5 sides.

In making the paneled fabric, it is preferred to have the fabric dry and to apply the wet plastic composition to said dry fabric, thereby providing a more intimate 10 connection between the composition and loose fibers when the composition is dried.

It is obvious that the described invention is susceptible of more or less modification so as to still be within the scope of the claims.

15 What I claim as new is:

1. A structural member, comprising open-mesh fabric of fibrous material, made of coarse vegetable fibers, such as those of Sisal grass, said fabric having numerous unfabricated fibers of said material protruding therefrom, and an artificial panel in which the meshes of said fabric and said unfabricated fibers are embedded.

2. A structural member, comprising a web 25 of open-mesh fabric of fibrous material, made of coarse vegetable fibers, such as those of Sisal grass, and separated artificial panels in which some of the meshes of said fabric are embedded, other meshes of said fabric 30 being left free at the lines of separation of said panels.

3. A structural member, comprising a web 35 of open-mesh fabric of fibrous material, made of coarse vegetable fibers, said fabric having numerous fibers of said material protruding therefrom and separated artificial panels in which some of the meshes of said fabric and some of said protruding fibers are embedded, other meshes of said fabric 40 being left free at the lines of separation of said panels.

4. In a wall or partition, a substantially 45 rigid skeleton structure, and members comprising open-mesh fabric of cord, composed of separate fibers, and panels bound to said

fabric, some of the meshes of said fabric being looped over some of the elements of said skeleton structure so as to connect the said members therewith.

5. In a wall or partition, a substantially 50 rigid skeleton structure, and members comprising webs of open-mesh fabric of cord, composed of separate fibers, and panels bound to said webs of fabric, some of the meshes of said fabric being looped over some 55 of the elements of said skeleton structure and connecting the said members in succession therewith.

6. In a wall or partition, a substantially 60 rigid skeleton structure comprising supporting members, members comprising webs of open-mesh fabric, separated panels thereon, and insert-rods supported by said supporting members and movable into and located in certain meshes of said webs of fabric to 65 support said webs in close succession.

7. A structural member, comprising a web 70 of open-mesh fabric of cord composed of separate fibers, and separated artificial panels in which some of the meshes of said fabric are embedded but exposed at corresponding sides of said panels, other meshes of said fabric being left entirely free between said panels.

8. In a wall or partition, a substantially 75 rigid skeleton structure, a member comprising a web of open-mesh fabric of cord composed of separate coarse fibers and separated artificial panels bound to said web, said web having some of said fibers loosely projecting 80 therefrom and beyond corresponding sides of said panels, and some of the meshes of said fabric being looped over some of the elements of said skeleton structure, and a layer of plastic material applied to the said fabric 85 and the said panels at said sides.

Signed at New York city, N. Y., this 26th day of November, 1917.

ALFONSO A. RICHARDSON.
